(57) **CLAIM**

The ornamental design for a first aid kit, as shown and described.

DESCRIPTION

FIG. 1 is an upper rear right side perspective view of a first aid kit showing the new design.

FIG. 2 is a rear elevation view of the first aid kit shown in FIG. 1.

FIG. 3 is a front elevation view of the first aid kit shown in FIG. 1.

FIG. 4 is a left side elevation view of the first aid kit shown in FIG. 1.

FIG. 5 is a right side elevation view of the first aid kit shown in FIG. 1.

FIG. 6 is a top view of the first aid kit shown in FIG. 1.

FIG. 7 is a bottom view of the first aid kit shown in FIG. 1; and,

FIG. 8 is an internal view of the first aid kit shown in FIG. 1.

The broken lines of the drawing represent stitching that forms no part of the claimed design.

1 Claim, 8 Drawing Sheets
